DESIGN FOR A COOKER PAIL OR THE LIKE

Wilfred D. Keith, Oakmont, Pa., assignor to The Aluminum Cooking Utensil Company, New Kensington, Pa., a corporation of Pennsylvania

Application April 10, 1939, Serial No. 84,178

Term of patent 7 years

To all whom it may concern:

Be it known that I, Wilfred D. Keith, a citizen of the United States, residing at Oakmont, in the county of Allegheny and State of Pennsylvania, have invented a new, original, and ornamental Design for a Cooker Pail or the like, of which the following is a specification, reference being had to the accompanying drawing, forming a part thereof.

Fig. 1 is a top plan view of a cooker pail embodying my new design; and Fig. 2 is an elevational view thereof showing the upper part of the cooker pail in section on the line II—II of Fig. 1.

The dominant feature of my design resides in the portion shown in solid lines.

I claim:

The ornamental design for a cooker pail or the like, substantially as shown and described.

WILFRED D. KEITH.
